Design No 443

Des. 443

James L. Jackson, New York, N.Y.
Letters Patent No 443. Dated Feb. 3. 1852.

The Schedule referred to in these Letters Patent, and making part of the same.

To all whom it may concern:

Be it known, that I, James L Jackson, of the City, County, and State of New York, have invented or produced a certain new and original design for a Grate Frame, and I do hereby declare the following to be a full, clear and exact description of the same, reference being had to the accompanying drawing, representing one half of the frame finished, the other half, which is the same in configuration, being in outline, and showing by section, the projections of the several parts thereof.

The general form of the frame is rectangular, with the outer margins finished by a delicate moulding and bead a. From the base b. on the jambs, starts a projection c, rising perpendicularly from said base, about half the height of the frame, when it sweeps round in a

semi-circular form, and rests on the opposite base of the jamb. On the face of said projection is a series of sunken latticed panelling *a*, separated by highly raised rosettes *c*, equidistant from each other. On a line with the top of the base *b*, inside of the projection *c*, starts a slightly curved stem *f*, with a leaf *g*, on its inner edge near the top, and which terminates in a volute *h*, curving towards, and meeting the moulding of the projection *c*, and between said stem and moulding, the space is filled up by a sunken latticed panelling *p*.

Over the volute *h*, is a Grecian cap, upon which is started a series of semi-elliptical scrolls *i*, with leaves *j*, in their centres, and terminating in a volute *k*, with three lozenges *l*, pendant, at the junction of the scrolls, and the space above their joinings filled up with two leaved volutes *m*, turning towards each other.

Underneath the scrolls *i*, which project from the general surface of the frame, commences a broad cavetto moulding *n*, which terminates in a delicate beading finished with a small plain moulding *o*.

The corners are finished by arabesque flowers and foliage in alto relivo, which shoot from a root *q*, in the lower corner of the panel *r*, surrounded by over hanging leaves *s*, thence springs up a rich leaf *t*, out of which rises two stems, the smaller of which entwines the larger, and terminates in a bud *u*. The larger stem curves round gracefully, partially covered by foliage, and terminates in a nearly full opened arabesque flower *v*, pendant. Out of the foliage of the larger stem starts a branch *w*, terminating near the corner of the panel in leaves *x*. The sections *A*, *B*, *C*, *D*, which are seen on the right of the drawing, represent the projection of the several parts herein enumerated.

Having thus described the nature of my design, what I claim therein as new, and desire to secure by Letters Patent, is the combination and arrangement of the ornamental figures herein represented, and forming an ornamental design for a Gate Frame. Ex'd
